Continuation of abandoned application Serial No. 725,890, February 1, 1947. This application February 16, 1953, Serial No. 337,036

4 Claims. - (Cl. 15—339)

1

This invention relates to a structurally and functionally improved nozzle and brush assembly and especially a nozzle which will be advantageous for use with a suction or vacuum cleaning apparatus.

It is an object of the invention to provide an assembly of this character which will be especially useful when employed on rugs and other floor coverings; the assembly being capable of having its parts adjusted so that they will cooperate to best advantage with the particular type of floor covering which is being cleaned.

A further object is that of furnishing a unit of this type which may readily be manipulated or adjusted by an inexperienced operator. This adjustment may be accomplished without a detailed visual inspection of the parts and with a minimum of effort.

A still further object is that of providing a nozzle and brush structure and in which the brush is floatingly mounted. In accordance with the present teachings, such mounting will nevertheless serve to maintain the brush in a position substantially parallel to the intake axis of the nozzle. However, as a consequence of the mounting, the brush may assume a position, tilted with respect to a transverse axis. This will permit it to conform to any inequalities of the surface which is being traversed and assure a proper and thorough cooperation of the brush with that surface.

An additional object is that of providing an assembly of this nature and in which the brush will be substantially self-cleaning when the assembly is in use. In other words, the brush may pick up thread and lint in the usual manner. However, due to the teachings of the present invention, these foreign materials will be automatically transferred to the suction apparatus. Therefore, the brush will at all times remain usable.

Another object is that of designing a unit which will include relatively few parts, each individually simple and rugged in construction; such parts being capable of ready manufacture by quantity production methods and being moreover capable of being assembled by relatively unskilled labor. When so assembled a unit is furnished which will operate over long periods of time with freedom from all difficulties.

With these and other objects in mind, reference is had to the attached sheets of drawings illustrating practical embodiments of the invention and in which:

Fig. 1 is a plan view of an assembly;

2

Fig. 2 is a partly sectional rear view thereof, taken along the lines 2—2 and in the direction of the arrows as indicated in Fig. 4;

Fig. 3 is a sectional view taken along the lines 3—3 and in the direction of the arrows as also indicated in Fig. 4;

Fig. 4 is an enlarged transverse sectional view of the assembly;

Fig. 5 is a sectional plan view taken along the lines 5—5 and in the direction of the arrows as indicated in Fig. 2;

Fig. 6 is a view similar to Fig. 2 but showing an alternate form of construction;

Fig. 7 is a transverse sectional view taken along the lines 7—7 and in the direction of the arrows as indicated in Fig. 6; and

Fig. 8 is a transverse sectional view taken along the lines 8—8 and in the direction of the arrows as indicated in Fig. 1 and illustrating particularly the positions which the brush is capable of assuming.

Referring primarily to Figs. 1 to 5, it will be seen that the reference numeral 10 indicates a hollow body to which a guard strip of rubber 11 or similar material may be secured. As shown the body 10 includes spaced main, front and rear walls through which air may flow. The underface of this body is hollow and is preferably defined by a sole plate IV which may have a chrome finish or be formed of highly polished metal such as stainless steel body.

As is shown, especially in Figs. 3 and 4, the plate 12 may be extended in the form of contact portions 12' for engagement with the surface being traversed. These contact portions are disposed adjacent the opposite ends of the body 10 and extend from the underface thereof. Substantially in line with the apex portion 13 of the body 10, this plate may be disposed in the form of a tubular part 17. Ridges 18 may define the zone between the contact portions 12' and the tubular part 17. The rear wall of body 10 prevents rearward movement of this tubular part.

The body 10 has an apex portion 13 terminating in a hub 15. Extending within the latter, as shown in Fig. 4, is a tube 14 which may be rotatable with respect to the hub. Inward movement of the tube 14 beyond the point illustrated is prevented by a flange 16. Outward movement thereof is prevented in a manner hereinafter brought out.

This tube 14 may have an angularly offset rear portion and is provided with a groove. Within the latter, a gasket 16' may be disposed. This gasket will serve to seal the parts against air

leakage. Also it will provide a friction element which will restrain undesired swiveling of the parts.

Rearwardly of the tube 17 the plate 12 may be interrupted by a slot. Extending through the latter is a brush comprising tufts of hair 18 and a backing strip 20. Bearing against this backing strip are coil springs 21, which tend to project the brush. Preferably the tufts of the latter normally extend in directions substantially parallel to the axis of tubular portion 17. The movement of the brush, as it is projected or retracted, is also preferably in such direction. A plate 22 is disposed to the rear of the brush and springs; this plate in effect furnishing the rear wall for the body 10 and providing in conjunction with the adjacent surfaces a brush well.

A collar 23 encircles the hub 15 and is rotatable with respect thereto. This collar has an inwardly extending flange 24 which bears against a rib 25, forming a part of tube 14. Collar 23 is restrained against rearward movement with respect to the parts in that plate 22 bears against the same; this plate being secured as a part of the nozzle assembly. The tube 14 being maintained by the collar 23, it follows that the rearward movement of the tube 14 is prevented although the latter will be free to swivel. A further extension 26 forms a part of flange 24. This extension, as shown especially in Fig. 2, presents a series of notches 27 in its inner face. These notches are connected by inclined surfaces which in aggregate define a cam portion.

As shown in Fig. 1 the ring 23 is also provided with a forward extension 28 which may be brought into alignment with indicating marks 29. The latter are associated with the body 10; the extension 28 transversing this indicates the ring 23 is rotated.

A plate 30 is mounted for sliding movement, preferably in the same space which receives the brush. Such mounting may be achieved, as shown in Fig. 5, by providing guiding portions 31 in the form of strips secured to the rear face of body 10. These guiding portions in effect furnish tracks to confine movements of the plate 30 to directions substantially parallel to the axis of tube 17. As will also be seen in this view, the body 10 may be extended rearwardly as 32, to in effect furnish well portions to receive the upper ends of the springs 21.

The plate 30 has its center portion notched or recessed as shown in Fig. 2. Extending rearwardly from this edge portion is a preferably integral part 33. The latter rides in contact with the notches 27 and surfaces extending between the same. The lower edge of plate 30 may be bent outwardly at a pair of spaced points. This has been indicated at 33'. These outward extensions conveniently project into the tufts 18 and underlie the backing strip 20.

As will be apparent the tube 14 may be connected to the wand or hose of a vacuum cleaning apparatus and the contact portions 12' of the plate 12 may ride in engagement with the surface to be cleaned. Under such circumstances the dust carrying air will be drawn past the ridges of lip portions 18, through the tube 17, towards the apex 13 of the body 10. This air will then flow rearwardly through the tube 14. As aforesaid, the latter is swiveled so that freedom of movement of the several parts will be permitted. Under such circumstances it will be assumed that the brush is retracted within the

space between the rear wall of the body 10 and plate 22.

Should the surface to be cleaned be of such nature that a brush should cooperate therewith, then the operator may simply rotate ring 23. With such rotation the extension 33, which has heretofore been resting within the extreme right end notch 27, as viewed in Fig. 2, will ride over the inclined surface to the next adjacent notch. Under the influence of springs 21 the brush will be projected as the extensions 33' lower to permit of this projection. As is apparent, the thrust of the springs 21 will be transmitted through these extensions 33' to the plate 30 and thus to the extension 33. The latter will, therefore, remain in firm contact with the face of the cam portion. Accordingly the brush will be protected beyond the plane of the contact portions 12'. This will assure a cooperation of the brush with the surface being cleaned. If a more vigorous engagement of the part is desired then continued rotation of the part of the ring 23 will allow that notched portion 27 which appears in the extreme left end of Fig. 2 to receive the extension 33. This distance between this notched portion and the center of the tube 14 being greatest, it follows that a corresponding projection of the brush will result. While only three notched portions 27 have been illustrated, it is apparent that a greater or lesser number of the same might be provided.

The same result is achieved by the form of construction shown in Figs. 6 and 7. In these views the numeral 34 indicates the body of the nozzle, which is formed with the usual opening 35 defining its under-face and this passages communicating with an apex portion in line with which a tubular part 36 is disposed. This tube may bear against an inner retaining ring 37 to limit its inward movement. An outer retaining ring 38 may encircle the tube 36 and be secured to the rear face of body 34 in a manner such as is indicated at 39. A plate 40 is secured to the rear edges of the body 34 at a point spaced from the nozzle portion 35 to provide a brush well.

Disposed within this space is a brush including a row of tufts or fibers 41 and a backing strip 42. A support 43 in the form of a plate, is slidably mounted between guides or rails 44. Leaf springs 45, conveniently in the form of inverted "V's" bear adjacent their ends against the upper edge of the backing strip 42. The apices of these springs may have bearing in abutments 46, formed in the body 34. Extensions 47 may form parts of the plate or shifting member 43 and extend in supporting relationship with respect to the backing strip.

It will be understood that the springs 45 will normally urge the brush to a projected position. The brush will be restrained from such movement by the extensions 47. A ring 48 may encircle the overlapping portions of body 34 and the tube 36 and be rotatable with respect to the same. This ring may support a housing portion 49, the inner surface of which is cam-shaped and tangentially disposed. This permits operations similar to those heretofore described under the reference numeral 27, in Fig. 2. An extension 50 forms a part of the actuator or plate 43 and rides within the surface of the housing 49. Therefore, the projecting tendency of the spring 45 is restrained. However, by rotating the ring 48 a greater or less projection of the brush may be assured.

It will be understood that in both of the illus-

trated embodiments the spring or springs are normally tending to project the brush. The cam structure serves to retract the same. Obviously, the parts can be arranged so that the reverse would be true. However, it is preferred that the functioning of the parts be as illustrated. Aside from other advantages, by having the springs normally tending to project the brush, any blow or strain on the latter will be cushioned. In other words, a force sufficient to cause the brush to retract will effect a withdrawal of the same into the nozzle body to a greater or lesser extent. Accordingly the probability of damage occurring will be reduced to a minimum.

As will also be apparent with respect to the brush, it may tilt around an axis transverse with respect to its body. In other words, in view of the manner in which it is supported, it will normally have its lower edge substantially parallel to the lower edge portions of the nozzle. However, if due to inequalities of the surface or otherwise more pressure is exerted against one end of the brush than against the other, the former end will be tilted upwardly. As soon as the pressure is relieved the parts will re-assume their normal positions.

Finally, with respect to this particular portion of the assembly, it will be observed as in both Figs. 4 and 7, that the brush is supported in a manner such that it may—within limits—move in any desired direction. In addition to the action brought out in the preceding paragraphs which results follow from this construction, it is apparent that the brush may incline or rock around its longitudinal axis. This has been generally indicated in Fig. 8. In that view there has been indicated the two different positions which the brush may assume incident to such pivoting. Position A is the one which the brush will normally assume when the nozzle is being moved in a forward direction, or in other words to the left as in this figure. When a rear stroke is undertaken then the brush will assume position B. As will be appreciated in connection with position A, the brush may readily pick up materials from the surface being cleaned. These may include dust particles, thread, lint, etc. When, however, the brush is traversing a surface and assumes position B, the tufts assume an inclined or tipped position. Under these circumstances and in co-operation with the surface being cleaned, lint, thread and other materials will be stripped from the tufts. These materials as freed will be drawn into the nozzle and so into the suction apparatus connected therewith.

Thus, among others, the several objects of the invention as specifically afore stated are achieved. Obviously numerous changes in construction and rearrangement of the parts might be resorted to without departing from the spirit of the invention as defined by the claims.

This application is a continuation of our prior application for United States Letters Patent Serial No. 725,890 filed February 1, 1947 and now abandoned.

What is claimed is:

1. In combination spaced front and rear walls connected to each other adjacent their upper and side edges to provide a hollow nozzle body the lower edges of which define an intake mouth, an outlet hub extending rearwardly from said body and communicating with the hollow interior thereof, a collar rotatably encircling said hub, an extension forming a part of said collar and providing an upwardly facing cam surface, a

brush and a plate mounted for sliding movement adjacent the outer face of said rear wall, an upper extension projecting laterally from said plate, a lower extension also projecting laterally from said plate, the lower of said extensions supporting said brush to restrain the same from downward movement, the upper of said extensions engaging said cam surface to have sliding movement with respect thereto, a spring bearing against said nozzle body and brush to urge the latter downwardly in the direction of the nozzle mouth and into firm contact with the lower plate extension supporting it, the plate being thereby urged in a corresponding direction and the upper extension of said plate accordingly bearing in sliding and firm contact with the cam surface.

2. In combination spaced front and rear walls connected to each other adjacent their upper and side edges to provide a hollow nozzle body the lower edges of which define an intake mouth, an outlet hub extending rearwardly from said body and communicating with the hollow interior thereof, a collar rotatably encircling said hub, an extension forming a part of said collar and providing an upwardly facing cam surface, a brush and a plate mounted for sliding movement adjacent the outer face of said rear wall, an upper extension projecting laterally from said plate, a lower extension also projecting laterally from said plate, the lower of said extensions supporting said brush to restrain the same from downward movement, the upper of said extensions engaging said cam surface to have sliding movement with respect thereto, a spring bearing against said nozzle body and brush to urge the latter downwardly in the direction of the nozzle mouth and into firm contact with the lower plate extension supporting it, the plate being thereby urged in a corresponding direction and the upper extension of said plate accordingly bearing in sliding and firm contact with the cam surface.

3. In combination spaced front and rear walls connected to each other adjacent their upper and side edges to provide a hollow nozzle body the lower edges of which define an intake mouth, an outlet hub extending rearwardly from said body and communicating with the hollow interior thereof, a collar rotatably encircling said hub, an extension forming a part of said collar and providing an upwardly facing cam surface, a brush and a plate mounted for sliding movement adjacent the outer face of said rear wall, an upper extension projecting laterally from said plate, a lower extension also projecting laterally from said plate, the lower of said extensions supporting said brush to restrain the same from downward movement, the upper of said extensions engaging said cam surface to have sliding movement with respect thereto, a spring bearing against said nozzle body and brush to urge the latter downwardly in the direction of the nozzle mouth and into firm contact with the lower plate extension supporting it, the plate being thereby urged in a corresponding direction and the upper extension of said plate accordingly bearing in sliding and firm contact with the cam surface and an extension forming a part of said collar adjacent the upper portion thereof and projecting in the direction of said front wall to traverse the surface of said nozzle body and indicate the posi-

tion in which said brush is retained by said spring and cam surface.

4. In combination spaced front and rear walls connected to each other adjacent their upper and side edges to provide a hollow nozzle body the lower edges of which define an intake mouth, an outlet hub extending rearwardly from said body and communicating with the hollow interior thereof, a collar rotatably encircling said hub, an extension forming a part of said collar and providing an upwardly facing cam surface, a brush and a plate mounted for sliding movement adjacent the outer face of said rear wall, an upper extension projecting laterally from said plate, a lower extension also projecting laterally from 15 said plate, the lower of said extensions supporting said brush to restrain the same from downward movement, the upper of said extensions engaging said cam surface to have sliding movement with respect thereto, spring strips disposed 20 in the form of inverted Vs, the arms of said springs bearing against said brush and the crotch portions thereof being supported by said body to urge said brush downwardly in the direction

of the nozzle mouth and into firm contact with the lower plate extension supporting it, the plate being thereby urged in a corresponding direction and the upper extension of said plate accordingly bearing in sliding and firm contact with the cam surface.
